UNITED STATES PATENT OFFICE.

WILLIAM E. HOKE, OF BALTIMORE, MARYLAND.

METHOD AND APPARATUS FOR FINISHING TAPER ARTICLES.

Application filed August 10, 1920. Serial No. 402,603.

To all whom it may concern:

Be it known that I, WILLIAM E. HOKE, a citizen of the United States, residing at 2008 North Charles Street, Baltimore, in the county of Baltimore City and State of Maryland, have invented certain new and useful Improvements in Methods and Apparatus for Finishing Taper Articles, of which the following is a specification.

10 My invention relates to improvements in the method and apparatus for finishing taper articles, such as twist drills, taper mandrels, and the like.

In the manufacture of twist drills, the usual method of procedure is to form the chip grooves or flutes in any suitable manner, as by milling out of a solid blank. The thus partially formed tool is then hardened which operation has a tendency to warp or 20 bend the drills. The drill must, if warped or bent, then be straightened; and the spiral lands are then ground slightly tapered, the diameter of the pointed portion of the drill being very slightly larger than that of the 25 shank end, this grinding operation requiring special machinery and must be performed on each individual drill.

It is the object of my invention to greatly simplify and to lessen the number of operations which have to be performed in finishing twist drills. This object I attain by subjecting a large number of hardened drill blanks to a simultaneous lapping by which they are ground to the desired taper form 35 and during the same operation straightened and reduced to the proper diameter.

The invention will be readily understood from the accompanying more or less diagrammatic drawings in which—

40 Fig. 1 is an end elevation, the work-holders being shown in section.

Fig. 2 is a plan of the machine with the upper lap removed.

Fig. 3 is a detail of the means for connecting the several work-holders.

Fig. 4 is a plan view of the work-holder, showing the drill-blanks located in the openings, and

Fig. 5 is a plan, looking down on the upper lap.

In carrying out my invention I use flat faced lapping blocks, one of which, A, may be stationary, while the other, B, is movable relatively to A. Both blocks may, however, 55 be reciprocated in opposite directions.

The working faces of the blocks, A and

B, are charged with suitable abrasive material in the usual way, and the lapping operation is carried out in the usual manner, oil or other liquid being used as a lubricant. 60

For reciprocating the block B, any suitable mechanism may be used, such as a connecting rod D, and crank E, driven by a pulley F. The connecting rod D is so connected to the block B, as to permit of free movement of this block; and for this purpose, a universal joint connection may be used. The block B is held against transverse movement by rollers G, supported on brackets H supported in any suitable manner. 65 Between the two lapping blocks are located work-holders, each of which may consist of a thin metal plate slightly less in thickness than the diameter of the finished drills, these plates having a series of apertures therein 70 preferably of sufficient width to contain several drills, and of a length just sufficient to permit insertion and withdrawal of the drills. These apertures are preferably arranged diagonally and are oppositely inclined in adjacent work-holders to counteract a tendency to side thrust. The several work-holders are detachably connected to each other by any suitable means, such as hooks, J, fitting into corresponding openings, K, so that as each work-holder is inserted at the front end of the machine, it can be attached to one already in the machine, while the work-holder containing finished drills can be readily detached from its 75 neighbor which is to remain in the machine. 80

The operation of the machine is commenced by locating one or two of the work-holders between the laps, and then successively attaching fresh work-holders at the 85 front and removing the work-holders containing the finished drills at the back of the machine.

The drill blanks are taken in the rough, as they come from the hardening operation; filled into the work-holders; subjected to the lapping operation in the machine until they are reduced to the proper diameter, and are delivered from the machine in finished condition. 100

When the sequence of operation has once been established it will be apparent that the upper lap will be inclined in the direction of the length of the drills from front to back of the machine, as indicated in Fig. 1, since the unstraightened and unground drills located 105 in the holders at the front of the machine are

of slightly larger diameter than the finished drills located at the back of the machine.

As a result of this operation the drills are given the desired taper, are perfectly straightened and the lands highly polished. The mechanism required is of the simplest character and no skilled operator is required for its operation. Further, a large number of drills can be simultaneously treated, thereby greatly reducing the cost of manufacture.

My invention is of particular importance in that it enables drills and like tapered articles of the smaller sizes to be economically and effectively straightened, tapered and polished in contradistinction to the usual practice in which no attempts are made to so finish the smaller size of drills.

It will be noted that the upper lap rests freely on the drills being lapped so that it can adjust itself to rest on the higher portions, which are thus gradually reduced to the desired size. The drills being lapped are free to rotate on their axes, but are restrained against longitudinal movement in the holder by abutment against the ends of the cavities in the work-holders. Because of the inclination of these cavities, the drills do not merely roll between the laps, but their surfaces are given an additional movement relative to the successive portions of the engaging surfaces of the laps, whereby a grinding action is produced.

Obviously the apparatus may take many varied forms, the particular form shown being illustrative of the general type of machine which I consider to be adapted for carrying out the method described.

Thus, the number of work-holders may be varied to thereby control the conditions of operation. With a smaller number of trays the taper imparted to the drills will be greater. With a larger number of trays and the taper will be less.

This will be apparent from the fact that the working surface of the upper lap is inclined to the working surface of the lower

lap, while the drills are inclined to the direction of relative movement of the laps. The inclination of the upper lap surface is 50 due to the fact that at the front it is resting on rough or oversize drills while at the back it is resting on finished drills of less diameter. By varying the distance from front to back of the machine, as by inserting 55 additional work-holders, the angle of inclination can be varied at will.

I claim:—

1. The method of finishing twist drills or the like which consists in subjecting a multiplicity of such articles to a simultaneous lapping between laps, one of which is freely floating, to which laps a relative movement of one lap with reference to the other is imparted, the articles to be lapped being arranged with their longitudinal axes at an angle to the direction of relative movement of the laps. 60

2. The method as claimed in claim 1, in which the drills are free to rotate on their axes while held against axially longitudinal movement. 70

3. The method as claimed in claim 2, in which groups of drills are caused to move in succession between the laps transversely 75 to the direction of relative movement of the laps.

4. An apparatus for finishing twist drills and the like comprising two lapping surfaces one of which is freely floating, means 80 for imparting relative movement thereto, a series of holders located between said surfaces each of less thickness than the finished drill, said holders having drill-receiving apertures therein arranged at an 85 angle to the direction of relative movement of the laps.

5. An apparatus as claimed in claim 4 in which the apertures in adjacent holders are inclined in opposite directions. 90

In testimony whereof, I affix my signature.

WILLIAM E. HOKE.
